MASS SPECTROMETER

William E. Stephens, Philadelphia, Pa.

Application April 5, 1947, Serial No. 739,681

1 Claim. (Cl. 250—41.9)

1

The present invention relates to improved mass spectrometry and particularly provides a method and apparatus for obtaining pulses of ions segregated according to mass-velocity relationships, collecting the ions to obtain pulses of current dispersed in time and recording the result.

A mass spectrometer is an apparatus for sorting ions according to the ratio of the mass of the ion to the charge that it carries (this ratio being referred to hereinafter as "specific mass") and can be employed for various purposes, including qualitative and quantitative analyses of mixtures containing different kinds of molecules, determination of isotope ratios, as a leak detector in any evacuated apparatus, etc.

A common form of mass spectrometer includes an ionization chamber in which molecules of the mixture to be analyzed are converted into ions, an analyzer tube in which a heterogeneous beam of the ions is separated by an electric or magnetic field into a plurality of diverging homogeneous beams of ions (the ions of the same specific mass being included in a single beam), an ion collector, means for bringing the several beams successively into contact with the collector and means for indicating separately the currents collected from the several beams.

There are numerous disadvantages to an instrument of the above type. Foremost among these is the high initial cost which is seldom less than \$25,000. Furthermore the instrument is bulky due to the magnet and its associated control equipment and extremely high voltages are necessary which endanger personnel.

This invention therefore has for its objects the provision of a mass spectrometer which is low in cost, which employs means for ion segregation without the use of a magnet, and employs low accelerating voltages.

The invention possesses numerous other objects and features of advantage, some of which together with the foregoing, will be set forth in the following description of specific apparatus embodying and utilizing the novel method and apparatus of this invention.

The present invention proposes a method for overcoming the disadvantages set forth above and is based on the principle that positive ions of different masses acquire different velocities when accelerated by a voltage potential according to the equation:

$$\text{Velocity} = \sqrt{\frac{2Ve}{m}}$$

where e is charge, V is voltage and m is mass. Thus ions of different mass gain different velocities. According to the invention, pulses of ions are selected at regular time intervals from an ordinary low voltage ion source and passed down a vacuum tube. In travelling down such a tube, a mixture of ions of different specific mass will separate into clusters of like mass and the different clusters will spread out in space by virtue of their difference in velocity. These ions are collected in a suitable manner, as in a Faraday cage, the resulting current amplified and impressed on the vertical plates of an oscilloscope whose sweep is synchronized with the pulse creating mechanism. A specific mass spectrum of the ions is thus exhibited on the screen of the oscilloscope. Separation of ions of different masses does not depend upon slit width as in the case for a conventional mass spectrometer, but depends only on the length of path, the accelerating voltage, pulse length and the detecting device. The proper choice of these variables depends upon what region of the mass spectrum is desired to be observed.

Such a mass spectrometer presents numerous advantages over present types. All magnets are done away with, eliminating the weight of the magnets and stabilizing equipment. The resolution does not depend on smallness and alignment of slits, etc. The ion spectrum is scanned at a rapid rate. The repetition time of the analysis is reduced to the periodicity of the pulsing frequency. The indication is continually represented visually and can easily be photographed.

These and other features of this invention will be more thoroughly understood in the light of the following detailed description taken in conjunction with the accompanying drawing in which the drawing is a diagram of one form of the mass spectrometer.

The spectrometer shown diagrammatically in the drawing consists of a sample chamber 10, an ionization chamber 11, an analyzer tube 12, a collector 13, an amplifier 14 and an oscilloscope 15. The ionization chamber and analyzer tube are enclosed in an air-tight container which is kept under high vacuum to avoid molecular and ionic collisions.

The gas to be analyzed is introduced into ionization chamber 11 through line 16 containing a capillary leak or gas inlet 17. In the ionization chamber the gases are bombarded by electrons from filament 18. This bombardment ionizes the molecules and they thereby become positive ions.

As a result of their positive charge the ions are accelerated toward slit 19 which is kept at a small negative potential with respect to the rest of the ionization chamber by means of battery 20. After passing through slit 19, the ions are further accelerated towards slit 21 which is kept at a larger negative potential with respect to slit 19 by means of battery 22. Positioned in the path of the ions emerging from slit 21 are deflecting plates 23 and entrance slit 24 to analyzing chamber 12. An alternating potential for example about 100 volts, is impressed across the deflecting plates by means of sweep generator 25, so that the ion beam is swept back and forth across the slit 24 with the result that a spurt of ions will pass through the slit as the beam passes the opening. The net result of this alternating potential on the deflecting plates is that the ions will travel down the tube as a series of pulses each of which is made up of ions of different masses. However, due to the mass-velocity relationships discussed above, each pulse will separate into clusters made up of ions of the same mass and consequently the same velocity. In order to identify the individual ions making up a cluster, it is necessary that the interval between pulses be great enough, for example, about one thousand times greater than the duration of the pulse, and that the length of the tube be short enough so that the fast ions of a succeeding pulse do not catch up with the slow ions of a preceding pulse. An exit slit 26 is placed in the path of the ions at the end of the tube through which the ions pass to a collector 27, which may suitably be a Faraday cage. The resulting current is amplified and impressed on the plates 28 of the oscilloscope 15 which deflect the oscilloscope beam vertically over the screen 29. The oscilloscope beam is swept horizontally as a function of time over screen 29 by connecting plates 30 of the oscilloscope with the sweep generator 25. Thus the horizontal sweep of the oscilloscope is synchronized with the pulse generating means connected to deflecting plates 23.

In this manner the type of ion is determined

by the relative position of its peak on the horizontal or time axis of the spectrogram and abundance of the same type of ions by the height of the peak. By proper calibration, quantitative determination of the atoms and molecules in gases and vapors may be had.

The nature and objects of the present invention having been thus described and illustrated, what is claimed as new and useful and is desired to be secured by Letters Patent is:

A mass spectrometer consisting of an elongated evacuated envelope, an inlet for the admission of a gas sample to said envelope, an electrical filament adjacent said inlet for ionizing the said gas sample, a first perforated plate spaced from said filament maintained at a negative potential whereby ions of the said gas sample are accelerated toward and through the perforation of the said perforated plate, a second perforated plate spaced from the first perforated plate, deflecting plates positioned between said first and second perforated plates maintained at periodically varying electrical potentials whereby said ions accelerated through the said first perforated plate are periodically caused to pass through the perforation of the said second perforated plate, and voltage sensitive ion collecting means spaced from said second perforated plate to collect ions passing through the said second perforated plate.
